CLAIM

The ornamental design for a candy cake candle, as shown and described.

DESCRIPTION

FIG. 1 is a front, top, and right side perspective view of a candy cake candle according to our new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view thereof; and,

FIG. 7 is a bottom plan view thereof.

The broken lines shown in FIGS. 1-6 illustrate portions of the candy cake candle, that form no part of the claimed design.
